UNITED STATES PATENT OFFICE.

THOMAS CLAXTON FIDLER, OF EMBERTON, ENGLAND.

IMPROVEMENT IN THE CONSTRUCTION OF BRIDGES.

Specification forming part of Letters Patent No. 174,510, dated March 7, 1876; application filed December 12, 1874.

To all whom it may concern:

Be it known that I, THOMAS CLAXTON FIDLER, of Emberton, in the county of Bucks, England, civil engineer, have invented Improvements in the Construction of Suspension-Bridges and Iron Arches, of which the following is a specification:

My said invention consists in a method of constructing suspension-bridges whereby the chains are so arranged and braced as to afford an inflexible support to the roadway, and to carry a passing load without distortion; and in order that my said invention may be fully understood I shall now proceed more particularly to describe the same, and for that purpose shall refer to the several figures on the annexed sheet of drawings, the same letters of reference indicating corresponding parts in all the corresponding figures.

Figure 1 of my drawings is an elevation of a suspension-bridge constructed according to my said invention.

a a are the piers, and *b b* the land-ties. In the place of a single chain from *c* to *h*, I employ two chains, (represented by the lines *c d e f g h* and *c i k f m h*), which are attached together, or to the same saddle, at *c* and *h*, and cross each other at *f*. The line *c i k f* is a parabolic curve, and the line *f m h* is a straight line, which forms a tangent to that curve at *f*. In like manner the chain *f g h* lies in a parabolic curve, and the chain *c d e f* in a straight line, which forms a tangent to that curve at the point *f*. The chains are united by the vertical struts *d i e k*, &c., and by the diagonal braces *d k i e*, &c. The roadway *r r* is attached to the chains by the rods *i r k r*, &c. If the half-span *c f* is uniformly loaded the load is carried by the chain *c i k f m h*, which forms a line of equilibrium for that load quite independently of what load there may be upon the other half-span. In like manner the chain *c d e f g h* is in equilibrium under any uniform load upon the half-span *f h*, so that each chain is under a uniform horizontal tension throughout its length so long as the two half-spans are uniformly loaded, though the load on one half may be greater than the load on the other half, and the braces have no strain upon them.

When either half-span is only partially

loaded the bracing is strained, and prevents any distortion of the chains, the chains and bracing together forming a rigid inverted bow-string rib. The bracing acting in this way increases the strain in certain parts of the chains, and lessens it in other parts, and I make the sectional area of the chains proportional to the secant of the angle of inclination at its different parts, just as in an ordinary suspension-chain, because the greatest horizontal strain is the same for every bar of the lower chain, and is nearly equal to the horizontal strain of the upper chain at *f*, but less than the greatest horizontal strain in the upper chains at *c* and *h*.

In bridges of large span, where the live load bears a small proportion to the dead load, the diminution of tension caused by an irregular loading of either half-span is not great, and I construct the chains of such bridges in any ordinary method, as shown in Fig. 2, which is a cross-section of the inverted bow-string rib formed by one-half of the bridge. *a* is the upper chain; *b*, the lower chain, and *c* is a vertical strut braced to resist compression.

In bridges where the live load bears a great proportion to the dead load the upper chain may at certain points be thrown into compression. Therefore, in small bridges, I substitute a rigid plate structure in place of the upper chain, as shown in the cross-section, Fig. 3, where the upper chain is replaced by the plates *a* and angle-irons *b*, which are capable of resisting either tension or compression. *d* is the lower chain, and *c* is a vertical strut built of plate and angle irons. The differences of strain caused by the said irregular loading are less when the upper chain is straight than when it hangs in a curve; therefore I construct all suspension-bridges with the upper chain straight.

In building arched structures on the same principle the two half-ribs, as seen in Fig. 4, are hinged at the abutments *a* and *c*, and hinged together at the crown *b*. Each half-rib has an upper flange, *a d b*, sharply curved, and a lower flange, *a e b*, less sharply curved, or straight. The flanges meet at *a* and at *b*, and are united in the middle by a plate or lattice-web *h*, and the flanges are so arranged

that the upper flange *d b* meets the center *b* in the same line with the flange *b g*.

Although the members *e* and *g* are here shown as not perfectly straight, the curvature is so slight as to be of no moment, since the said members are in effect rigid.

The principles before stated as applying to the suspension-bridge apply also to the arch, with the difference that the flanges are in compression instead of in tension. A certain irregularity of loading might throw the lower flange *a e b* into tension; but, as this is of no consequence, the lower flange may be curved, and not straight.

Fig. 5 is a cross-section of an arch-rib of wrought-iron, the upper flange *a b* and the lower flange *d e* being built of plate and angle iron united by the plate or lattice-web *c*. Fig. 6 is a cross-section of an arch-rib of cast-iron, in which the flanges *a* and *b* and the web *c* are cast in one piece. The suspension-bridge may also have the cross-section shown in Figs. 5 or 6, and may be constructed exactly as the arch inverted.

The half-ribs of the suspension-bridge are in any case either actually or virtually hinged to the piers at *c* and *h*, Fig. 1, and hinged together at *f*. The upper and lower chains or flanges may be actually hinged together and with the saddle at *h*, or the two chains may be separately attached to the saddle, as shown in Fig. 7, in which *a d* is a bar of the upper chain; *b c*, a bar of the lower chain, attached by the pins *a* and *b* to the saddle-plates *e*. The pins *a* and *b* are placed in the line of the bar *b c*, so that a small angular motion of the whole half-rib would produce no sensible strain upon either bar. In the same way the two half-ribs may be actually hinged together at *f*, Fig. 1, or the two chains may cross each

other, the flat links of one chain passing between those of the other chain; or the upper and lower chain of each half-rib may be separately attached to junction-plates, as shown in Fig. 8, in which *p* is the junction-plate, to which are attached the chains *a b* and *e f* of the left half-rib, and the upper chain *g h n* and lower chain *c d e* of the right half-rib, the centers *b*, *c*, *f*, and *g* being arranged in the lines of the bars, or nearly so, in the same way as in Fig. 7. *i* is a vertical strut in the right half-rib, and *k l* the diagonal braces, cottered up to an adjusting-plate, *m*.

I do not desire to claim, broadly, a suspension-bridge constructed with two chains attached to the same piers and crossing each other at the center; but

I claim—

1. A suspended or arched structure, in which two half-ribs are jointed together at the center of the span, each half-rib consisting of a straight member and a curved member, so arranged that the straight member of one half-rib forms a tangent to, or a direct continuation of, the curved member of the other half-rib, substantially as described.

2. The two half-ribs, constructed of plate and angle iron, substantially as described, and hinged to each other and to the piers or saddles, as set forth.

In witness whereof I have signed my name to this specification in the presence of two subscribing witnesses.

T. C. FIDLER.
